MAILBOX

Irving Levine, Woodmere, N. Y.

Application June 20, 1955, Serial No. 36,596

Term of patent 14 years

(Cl. D74—9)

The figure of the drawing is a front perspective view of a mailbox showing my new design. The end of the mailbox opposite to that shown on the drawing presents a substantially similar appearance.

I claim:

The ornamental design for a mailbox, substantially as shown and described.
